Arthur C. Fraser & Co.

UNITED STATES PATENT OFFICE.

PHILANDER ANDERSON, OF NEW YORK, N. Y.

VICE.

SPECIFICATION forming part of Letters Patent No. 661,942, dated November 20, 1900.

Application filed January 8, 1900. Serial No. 546. (No model.)

To all whom it may concern:

Be it known that I, PHILANDER ANDERSON, a citizen of the United States, residing in the city, county, and State of New York, have invented certain new and useful Improvements in Vises, of which the following is a specification.

This invention relates to clamping-tools, and aims to provide certain improvements therein especially applicable to bench-vises.

Heretofore bench-vises have been constructed with a base-plate for attachment to a bench, a fixed jaw the stock of which has been sometimes swiveled to the base-plate to permit turning on a vertical axis, a movable jaw connected to the stock by a sliding guide-bar, and a screw carried by the movable jaw and engaging the stock for forcing the jaws together.

My invention aims to provide various improvements in vises of this general class, and especially to provide a vise in which the jaws can be set in any desired position.

To this end in carrying out the preferred form of my invention as applied to a bench-vise I provide means whereby the jaws can be adjusted to various positions around a plurality of axes, giving the jaws a substantially universal adjustment, also improved means for holding the jaws in their various positions, and various improvements in the construction and arrangement of the parts, all of which will be hereinafter fully set forth.

In the accompanying drawings, Figure 1 is a side elevation, partly in vertical longitudinal mid-section, of a bench-vise, the parts being shown in full lines in the position of an ordinary vise and in dotted lines in one of the positions permitted by my improvements and the bench being shown fragmentarily. Fig. 2 is a front elevation thereof, showing the parts in full lines in the position of an ordinary vise and in dotted lines in another position permitted by my invention. Fig. 3 is a plan view thereof. Fig. 4 is a vertical section cut in the planes of the line 4-4 in Fig. 1 and looking in the direction of the arrow. Fig. 5 is a plan view of the movable base-plate, and Fig. 6 is a plan view of the bench base-plate. Referring to the drawings, let A indicate a bench or support, and B the stock, C the fixed jaw, and D the movable jaw, of a vise or tool

carried thereby. The movable jaw has a guide-bar E, movable through the socket F in the stock, and carries a screw G, which engages a nut H in the stock for operating the movable jaw. A handle I is provided for manipulating the screw. As thus far described, the parts may be of any usual or suitable construction for clamping articles to be operated upon or for other analogous purposes, the parts shown being taken as convenient examples for illustrating my improvements.

According to the preferred form of my invention, which I will now describe in detail, I provide means for permitting general adjustment of the jaws both angularly and bodily relatively to the bench, preferably providing an improved fixed base-plate J for attachment to the bench, a movable carrier-plate K, adjustably connected to and carried by the base-plate near its outer edge on the one hand and adjustably connected to and carrying the base L of the stock B on the other hand. The plate J is fixed to the bench or support, as by lag-screws a traversing lugs b in an extension c of the plate, and a bolt d passing through the rear lug and the bench and fastened by a nut e beneath the latter. The base has a finished top bearing f, and the plate K has a reciprocal bottom bearing g for resting on the face f when the vise is in the ordinary horizontal position. The base J and carrier-plate K are adjustably connected together on an axis angular to the vertical, so that the carrier-plate can be adjusted from a horizontal position to various oblique positions around this axis, and when turned on this axis receives also a bodily movement outward from the support, so as to permit a freer movement of the bar I. As shown, an axis M constitutes the connection between these parts, around which their relative movement is effected, the base-plate J being provided with a forwardly and downwardly depending lug N, and the carrier-plate K being provided with a reciprocal lug O, which passes through a slot P in the base-plate, so that the adjacent faces i of these lugs fit against each other on a plane coinciding with the vertical longitudinal plane through the axis of the base-plate and an appreciable distance outward from said axis. An axial pin j passes through holes k in the lugs to connect them together,

the pin having a head *l* on one side, a screw-threaded end *m* at the opposite side of the opposite lug, and a handle clamp-nut *Q*, screwing on the screw-thread for clamping the lugs together with sufficient force to hold them in any position in which they are set. The base-plate *J* and the carrier-plate *K* also have supplemental locking provisions for holding them in the normal position, these preferably consisting of a lug *R* on the carrier-plate engaged by a lock-bolt *S* on the base-plate. The base-plate is shown as formed with a socket *n* for receiving the lug *R* and with a socket *p* for the bolt *S*. The latter is shown as pressed 15 toward the locking position by a spring *r*, which is confined between the bolt and the head of the bolt *d*, being shown as mounted on a pin *s*, traveling in a hole *t* in the bolt *d*. Preferably the top of the bolt and the bottom 20 of the lug *R* are slightly beveled, so that the bolt may be sprung back as the parts come together, and the lug is formed with a notch for receiving the bolt at the proper position to lock the carrier-plate as soon as it is properly seated on the base-plate. The lock and the pivot being as far apart as possible—the full width of the carrier-plate—secures the greatest possible rigidity when the vise is in the upright position. The stock is preferably 25 adjustably connected to the carrier-plate *K*, so that it can be swung laterally thereon to any position, this being accomplished in the construction shown by forming the base *L* of the stock with a smooth bottom bearing-face 30 *u* for fitting on the top face *v* of the plate and by swiveling these parts together on a vertical axis in any suitable manner, as by a swiveled stud *T*, which is screwed into the bottom of the stock and passes through an 35 axial hole *w* in the carrier-plate, having a projecting head seated in a socket *y* in the under face of the carrier.

For locking the stock against rotation on the carrier a lock is provided, which is preferably the lock *U*, (shown in Figs. 1, 3, and 4,) comprising a series of sockets *x* on the carrier-plate and a bolt *z* on the stock, the sockets being arranged around the axis of the stud *T*, so that the bolt will pass over them when 40 the stock is rotated and can be snapped into an adjacent socket when the stock is to be locked in position. The lock *U* is preferably formed by a shell *a'*, cast integrally with the stock and having a socket *b'*, within which the bolt is placed, so that its upper end projects above the shell, where it is engaged by a handle *c'*, having a cam-face *d'*, and pivoted to the end of the bolt in such manner that when 45 the handle is turned down its narrow edge *e'* will be opposed to the top of the shell and permit complete descent of the bolt, and when it is turned up its cam-face will ride on the top of the shell and lift the bolt above the notches. For depressing the bolt a spring *e* 50 is confined within the shell and reacts against the top of the latter and against a pin *f'* on the bolt.

In use the vise will be locked in the normal or usual position, with the carrier-plate and base-plate fixed together, whereupon the stock 70 can be turned on a vertical axis like an ordinary bench-vise. In this condition it will have as much strength and rigidity as an ordinary vise and will have the advantage that the improved lock *U*, being on top and easily 75 accessible, can be readily operated to lock the vise in any position and will positively hold it in any position for which the lock is adapted. If any other than the ordinary position is desired, the user can immediately release 80 the carrier-plate by freeing the lock *S* and the clamp-screw *Q*, whereupon the jaws can be tilted around a horizontal axis to any position and immediately locked by setting the clamp-screw, one position being shown in Fig. 85 1. It will be observed that by placing the axis *M* at one side of the vertical axis I am enabled to mount the vise on an ordinary bench or work-table without cutting away the edge, and yet extend the horizontal pivot to any desired distance downward. The downward extension of this pivot is very useful in securing a long radius of movement, so as to throw the jaws and the operating-bar outward from the bench when the vise is turned on this 90 pivot, giving freer access to the operating-bar than if the parts were close to the table, and even with a slight downward extension of the axis *M* its outward position secures an outward movement from the table of the stock 95 and connected parts in addition to their angular movement, which would not be the case if the axis *M* were in the same plane with or intersected the vertical axis. After the clamp-screw is set the jaws may be revolved on the 100 carrier-plate to bring them to any other position desired, one such position being shown in dotted lines in Fig. 2. In this way the vise can be adjusted almost universally to give the 105 position best suited to convenient operation on each portion of the work to be done without necessitating a resetting of the work, the setting of the vise being much more convenient and rapid than would be the setting of the work it held in ordinary cases. 110

It will be seen that my invention provides improvements which can be readily and advantageously availed of, and it will be understood that I do not limit myself to the particular details of construction, arrangement, and combination set forth as constituting the preferred form of my invention, since my improvements may be availed of in whole or in part, according to such modifications as circumstances or the judgment of those skilled 115 in the art may dictate, without departing from the spirit of the invention.

What I claim is—

1. In vises and like tools, the combination 120 of the tool proper with a support therefor, and a pivotal connection between said tool and support, said pivotal connection being below and approximately at the outer edge of said support. 125

2. In vises, a pair of clamping-jaws, a base-plate J and means for attaching said base-plate to a bench, in combination with a carrier connecting the jaws and base-plate, a hinge connection having a horizontal axis between the carrier and base-plate and approximately at the edge of said base-plate, and a swivel connection having a vertical axis between the carrier and one of the jaws. 35
- 10 3. In vises, a pair of clamping-jaws, a base-plate J and means for attaching said base-plate to a bench, in combination with a carrier connecting the jaws and base-plate, a hinge connection having a horizontal axis between the carrier and base-plate and approximately at the edge of said base-plate, and a swivel connection having a vertical axis between the carrier and one of the jaws, and means for fixing the carrier and base-plate 40 rigidly together in any position of adjustment. 15
- 15 4. In vises, a pair of clamping-jaws, a base-plate and means for attaching said base-plate to a bench, in combination with a carrier connecting the jaws and base-plate, a hinge connection having a horizontal axis between the carrier and base-plate and approximately at the edge of said base-plate, and a swivel connection having a vertical axis between the carrier and one of the jaws, and means for 45 fixing the carrier and the jaw it carries against relative movement in any of several positions of adjustment. 20
- 20 5. In vises, jaws C and D, in combination 25 with a stock B having a base L, a base-plate J, a carrier K movably connected to said base-plate, a movable connection between the carrier and said stock, and means for fixing the carrier and base-plate together, and means for fixing the carrier and stock together. 30
- 25 6. In vises, jaws C and D, in combination with a stock B having base L, a lock U carried by said base, a carrier K fitting said base, a swivel connection between the carrier and base, a base-plate J, a swivel connection between the base-plate and carrier, a clamp for 45 locking the base-plate and carrier in any of various positions, and a lock for locking said parts in one position. 35
- 30 7. In vises and other tools, the combination of the tool proper with the improved base-plate J having lug N, slot P, socket n, and top face f, substantially as and for the purpose set forth. 40
- 35 8. For vises, the improved carrier-plate K having lug O, projection R, top and bottom 45 bearing-faces g and v, and axial hole w in combination with jaws carried by said plate and a support for said plate. 50
- In witness whereof I have hereunto signed my name in the presence of two subscribing 55 witnesses.

PHILANDER ANDERSON.
